UNITED STATES PATENT OFFICE.

ROBERT CRITSER AND ROBERT C. WRIGHT, OF LAPEL, INDIANA.

DUMPING-WAGON.

No. 849,056.

Specification of Letters Patent.

Patented April 2, 1907.

Application filed February 6, 1907. Serial No. 356,052.

To all whom it may concern:

Be it known that we, ROBERT CRITSER and ROBERT C. WRIGHT, citizens of the United States, residing at Lapel, in the county of 5 Madison and State of Indiana, have invented a new and useful Dumping-Wagon, of which the following is a specification.

This invention relates to dumping-wagons of that type in which the bottom of the wagon-body is made up of movable sections.

The object of the invention is to provide a wagon-body having a sectional bottom, the members of which can be readily raised into closed position and firmly supported, so as to 15 prevent displacement thereof.

A still further object is to provide simple and effective means for simultaneously releasing the bottom-sections to permit them to swing downward by gravity and discharge 20 the load therebetween.

With these and other objects in view the invention consists of certain novel features of construction and combinations of parts, which will be hereinafter more fully described, and pointed out in the claims.

In the accompanying drawings is shown the preferred form of the invention.

In said drawings, Figure 1 is a longitudinal section through the wagon and showing the 30 bottom-section released or unsupported. Fig. 2 is a front elevation of the wagon-body. Fig. 3 is a section on line $x-x$, Fig. 1; and Fig. 4 is an enlarged longitudinal section through a portion of the body and showing the bottom-sections in raised or closed position, said sections being shown by dotted lines in lowered position.

Referring to the figures by characters of reference, 1 are side beams suitably supported by the wheels 2 of the wagon, and each of these side beams has an inwardly-extending longitudinal flange along its upper edge, as shown at 3, said flanges constituting guides. Studs 4 extend inward from the 45 beams 1, below the flanges 3, and carry friction-rollers 5.

Connecting the flanges 3 are cross-rods 6, spaced apart at regular intervals, and upon each of these rods are secured hinge-straps 7, 50 riveted or otherwise fastened to the bottom-section 8, preferably formed of sheet metal. The straps 7 extend across the bottom-section and are folded to form inclined faces 9 and bowed seats 10. The inclined portions 9 are disposed adjacent the pivot-rod 6, to which the straps are connected, while the

seats 10 are interposed between the inclined portions and the free longitudinal edge of the bottom-section.

Slidably mounted upon the supporting-rollers 5 and beneath the flanges 3 are bars 11, connected by cross-rods 12, disposed at distances apart equal to the distances between the pivot-rods 6. Lifting-rollers 13 are mounted on these rods 12 and are adapted when the bottom-sections are raised or closed to rest beneath and support the bowed seats 10.

A rock-shaft 14 is mounted in hangers 15, depending from the front portions of the 70 beams 1, and arms 16 extend therefrom and are connected to the bars 11 by links 17.

A lever 18 extends from one end of the shaft 14 to a point within convenient reach of the driver.

The wagon herein-described is particularly designed for holding gravel and the like, and when the bottom-sections are raised they completely close the body 19 of the wagon. Moreover, it will be noted that when the sections 80 are thus disposed the bowed seats 10 rest upon the supporting-rollers 13, and the weight of the contents of the wagon presses the sections 8 downward with sufficient force to prevent the rollers 13 and the bars 11 from 85 moving out of adjusted position. When it is desired to dump the contents of the wagon, the lever 18 is swung so as to cause arms 16 to pull forward on the bars 11. The rollers 13 will therefore be pulled out of the bowed 90 seats 10 provided for them and under the inclined portions 9 until they finally assume positions below the rods 6. The sections 8 are therefore free to drop by gravity, and the contents of the wagon will be discharged between them. To return the sections 8 to their 95 raised positions, the movement of the lever 18 is reversed, and the rollers 13 are therefore forced against the inclined portions 9, so as to deflect the bottom-sections upward. Said 100 rollers 13 then pass beneath the bowed seats 10, which by reason of their peculiar contour serve to lock the rollers, so as to prevent the bars 11 from sliding under ordinary conditions.

It will be noted that the flanges 3 not only constitute guides for the bars 11, but they also protect said bars and the rollers 5 from the material discharged between the bottom-sections. The apparatus is very simple and durable in construction and can be easily operated either to dump the wagon or to return

the bottom-sections to their raised or closed positions. Although the invention has been described and shown applied to a wagon-body it is to be understood that the same may be used in connection with car-bodies or any receptacles designed to have their contents discharged through the bottoms thereof.

What is claimed is—

1. The combination with a plurality of pivotally-mounted bottom-sections; of a slideable series of lifting and supporting rollers movable below the pivots of said sections.
2. The combination with a plurality of pivotally-mounted bottom-sections; of a slideable series of lifting and supporting rollers, and means carried by each bottom-section and in the path of one of the rollers for facilitating the shifting of the sections into closed position.
3. The combination with a plurality of pivotally-mounted bottom-sections; of a slideable series of actuating devices, and deflecting means upon the bottom-sections and in the paths of said devices.
4. The combination with a plurality of pivotally-mounted bottom-sections; of an inclined deflecting device upon each section, a seat integral with said device, and movable means for successively contacting with the inclined portion and the seat to shift and support the bottom-section.
5. The combination with a plurality of pivotally-mounted bottom-sections, and a bowed seat carried by each of said sections; of a plurality of simultaneously-movable actuating devices disposed to contact with and be held against movement by said seats and to support the sections in closed position.
6. The combination with a plurality of pivotally-mounted bottom-sections; of simultaneously-movable lifting and supporting devices, and means upon the sections for holding said devices against accidental displacement.
7. The combination with a plurality of pivotally-mounted bottom-sections; of a series of rotatable lifting and supporting devices, means upon each of the bottom-sections for holding said devices against accidental displacement, and deflecting portions upon the sections for directing said devices against the holding means.
8. The combination with a plurality of pivotally-mounted bottom-sections, a bowed seat upon each of said sections, and an inclined portion extending from said seat; of a plurality of simultaneously-movable lifting

and supporting devices for successively contacting with the inclined portions and the seats of the respective sections.

9. The combination with a plurality of pivotally-mounted bottom-sections, a concave seat upon each section, and an inclined portion extending from each seat; of a plurality of simultaneously-movable rollers disposed to successively contact with the inclined portions and seats, and means for actuating the rollers.

10. The combination with a plurality of pivotally-mounted bottom-sections; of connected side bars, rollers carried thereby and movable against the respective bottom-sections, guides for the side bars, and manually-operated means for actuating the side bars.

11. The combination with side beams, friction-rollers thereon, and guide-flanges adjacent the rollers; of a plurality of pivotally-mounted bottom-sections interposed between the flanges, side bars movably mounted between the flanges and friction-rollers, rollers carried by the side bars and movable simultaneously against the respective bottom-sections, and manually-operated means for actuating the side bars.

12. The combination with a receptacle; of a closure pivotally mounted therein, a bowed seat upon said closure, an inclined portion extending from said seat, and a shiftable lifting and supporting device disposed to successively contact with the inclined portion and the seat.

13. The combination with a receptacle; of a closure pivotally mounted therein, a combined lifting and supporting device movable against the closure, and means upon said closure for holding the device against accidental displacement while supporting the closure.

14. The combination with a receptacle; of a closure pivotally mounted therein, a combined lifting and supporting roller, means for shifting the roller against the closure to raise and support it, and non-yielding means carried by the closure for holding the roller against accidental displacement while supporting the closure.

In testimony that we claim the foregoing as our own we have hereto affixed our signatures in the presence of two witnesses.

ROBERT CRITSER.
ROBERT C. WRIGHT.
